US0D1092573S

(12) **United States Design Patent** (10) Patent No.: **US D1,092,573 S**
(45) Date of Patent: ** Sep. 9, 2025

(54) **REFRIGERATOR**

(71) Applicant: **Samsung Electronics Co., Ltd.**, Suwon-si (KR)

(72) Inventors: **Hyunseok Kang**, Suwon-si (KR); **Hyun-Joo Sim**, Suwon-si (KR); **Myung-Kyu Kim**, Suwon-si (KR); **Selim Yoon**, Suwon-si (KR)

(73) Assignee: **Samsung Electronics Co., Ltd.**, Suwon-si (KR)

(**) Term: **15 Years**

(21) Appl. No.: **29/937,535**

(22) Filed: **Apr. 16, 2024**

(30) **Foreign Application Priority Data**

Oct. 16, 2023 (KR) 30-2023-0040248

(51) **LOC (15) Cl.** **15-07**

(52) **U.S. Cl.**

USPC **D15/91**

(58) **Field of Classification Search**

CLAIM

The ornamental design for a refrigerator, as shown and described.

DESCRIPTION

FIG. 1 is a front perspective view of a refrigerator showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion 8 in FIG. 1;

FIG. 9 is an enlarged view of the encircled portion 9 in FIG. 1;

FIG. 10 is an enlarged view of the encircled portion 10 in FIG. 1;

FIG. 11 is an enlarged view of the encircled portion 11 in FIG. 2;

FIG. 12 is an enlarged view of the encircled portion 12 in FIG. 2;

FIG. 13 is an enlarged view of the encircled portion 13 in FIG. 2;

FIG. 14 is an enlarged view of the encircled portion 14 in FIG. 2;

FIG. 15 is an enlarged view of the encircled portion 15 in FIG. 3;

FIG. 16 is an enlarged view of the encircled portion 16 in FIG. 4;

FIG. 17 is an enlarged view of the encircled portion 17 in FIG. 4;

FIG. 18 is an enlarged view of the encircled portion 18 in FIG. 5;

FIG. 19 is an enlarged view of the encircled portion 19 in FIG. 5;

FIG. 20 is an enlarged view of the encircled portion 20 in FIG. 5;

FIG. 21 is an enlarged view of the encircled portion 21 in FIG. 5;

FIG. 22 is an enlarged view of the encircled portion 22 in FIG. 6;

FIG. 23 is an enlarged view of the encircled portion 23 in FIG. 6;

FIG. 24 is an enlarged view of the encircled portion 24 in FIG. 6;

FIG. 25 is an enlarged view of the encircled portion 25 in FIG. 7; and,

FIG. 26 is an enlarged view of the encircled portion 26 in FIG. 7.

The evenly-dashed broken lines in the figures depict portions of the refrigerator that form no part of the claimed design.

The dot-dash broken lines encircling portions of the claimed design that are illustrated in enlargements form no part of the claimed design.
